UNITED STATES PATENT OFFICE

ARTHUR F. PYM, OF SWAMPSOOTT, MASSACHUSETTS, ASSIGNOR TO UNITED SHOE MACHINERY CORPORATION, OF PATERSON, NEW JERSEY, A CORPORATION OF NEW JERSEY

SHOE CEMENTER

Original application filed June 3, 1921, Serial No. 474,701. Divided and this application filed November 10, 1927. Serial No. 232,330.

This invention relates to shoe machinery, and is illustrated as embodied in an apparatus for operating on the insides of shoes. The present application is filed as a division 5 of my copending application Serial No. 474,701, filed June 3, 1921, which has matured into Letters Patent of the United States No. 1,693,667, granted Dec. 4, 1928, and discloses the invention in a form adapted for 10 use in connection with the operation of securing the linings in turn shoes, although the invention is not limited to such use.

In making turn shoes with sewed heel seats, the lining is not sewed in at the bottom around the heel seat, but is attached by adhesive after the shoe has been turned, a shank piece being thereafter inserted to cover the margin of the lining at the heel seat, and to extend forward approximately to the ball 15 line. So far as I am aware, these various operations of securing the lining and shank piece in place have always been performed by hand, the adhesive being applied by a brush, the lining "laid" or smoothed against the adhesive by the fingers of the operator, and a shank piece thereafter inserted in the 20 shoe.

One object of the present invention is to 25 improve the making of turn shoes by providing mechanical means for coating the inside of a shoe with adhesive so that when the lining is subsequently laid it will be held in place by the adhesive. With this object 30 in view, one feature of the invention resides in the provision, in a shoe machine, of a fixed- 35 ly mounted support for a shoe and means for coating the lateral faces of the inside of a bottomed shoe supported thereby.

The illustrated mechanism for applying 40 the adhesive comprises a coating device in which a brush, or equivalent applying member, transfers the liquid from a receptacle and applies it to the inside of the shoe. To 45 secure uniformity in the coating, the brush is shown as rotated by suitable power-driven mechanism, and to insure that the adhesive will be applied correctly, a shield member serves also to guide the shoe to position over 50 the brush and also protects the fore portion

thereof from possible engagement with the brush.

One of the great difficulties in any adhesive-applying device is the readiness with 55 which practically all adhesives cake or crust under the influence of the atmosphere. I have arranged my improved apparatus to minimize this action by restricting the access of the atmosphere to the adhesive in the reservoir. A very small opening, but slightly 60 larger than the cross-section of the brush, is provided for the insertion of the brush, and even this small opening is normally almost 65 entirely closed by the brush. To make this possible, the brush itself is mounted in a novel manner for axial movement into and 70 out of the receptacle. Moreover, only a small quantity of adhesive is supplied to the brush at any one time, being just sufficient 75 for the next shoe, and the remainder is kept in a sealed reservoir where the atmosphere cannot reach it. This small quantity of fresh adhesive is supplied each time the brush is raised to a small receptacle, slightly 80 larger than the brush, so that the brush itself, in descending, acts as a piston to force the adhesive upward and distribute it to the 85 whole surface of the brush.

These and other features of the invention, 90 including details of construction and combinations of parts, will be apparent from the following description of the illustrative embodiment of the invention shown in the accompanying drawings, in which

Fig. 1 is a view, partially in side elevation and partially in section, of the adhesive-applying mechanism, and

Fig. 2 is a view of a turn shoe, partially 95 broken away, illustrating the manner in which the inside of the shoe is coated with adhesive.

The coating mechanism 100 comprises a brush 102 carried by a shaft 104 which is mounted for rotation thereby to turn the brush around its axis and for axial movement 95 to carry the brush from a lower position where it receives adhesive to a raised applying position. The shaft 104 is rotated continuously during the operation of the machine by a train of gears 106, 108, 110, 112 100

and 114. Gear 106 is fixed on a drive shaft 30 and the gear 114 is provided with a key or lug riding in a keyway 116 of the shaft 104. By this arrangement the train of gears is continuously driven and shaft 104 is rotated by gear 114 in both raised and lowered positions. A sleeve 118 is secured to the shaft 104 in any desired and well-known way to permit rotation of the shaft within the sleeve and is arranged to be raised and lowered by a lever 120 acting through a pin-and-slot connection 122 to move the shaft 104 axially. The lever 120 is lowered by a coil spring 124 and is raised at the will of the operator by a cam 126 acting against cam roll 128. Cam 126 is secured to a sleeve (not shown) which also carries a Horton clutch 132 arranged in the usual way to be secured to the shaft 30 or to be released therefrom by the engagement of abutments 134 and 136 with a pawl 138 mounted on a bell-crank lever 140 operated by treadle rod 142 and a treadle (not shown). The shaft 30 is adapted to be connected with a suitable source of power and to be rotated constantly during the operation of the machine. A bracket 146 on the support 20 carries a reservoir 148 for the adhesive.

By the above arrangement of parts the brush 102 is continuously rotated and is controlled by the treadle to be raised axially out of the adhesive in the receptacle 148 by the first depression of the treadle and lowered again into the adhesive upon a second depression of the treadle. If preferred, the abutment 134 might be omitted on the Horton clutch, in which case operation of the treadle would result in axial movement of the shaft 104 to raise brush 102 out of the adhesive in receptacle 148 long enough to place a shoe thereover to coat the interior counter portion and to remove it again, after which the brush would automatically descend again into the adhesive.

The forward part of the shoe is protected from possible engagement with the brush 102 by a shoehorn-like shield or support 150 fixedly supported out of contact with said brush, as best shown in Fig. 2, which also acts as a guide when positioning the shoe over the brush for the application of paste to the inside of the shoe.

The reservoir 148 is hermetically sealed by a cover 152 secured thereto by clamping nuts 158. A filling opening in this cover is normally sealed by a threaded cap 160. The central portion of the cover is formed into an inner receptacle 154, of slightly larger diameter than brush 102, in the bottom of which are holes 156 communicating with the inside of reservoir 148. By this arrangement, when brush 102 is raised, adhesive flows from reservoir 148 into receptacle 154 up to the top of holes 156, at which height it is held by the pressure of the atmosphere.

When brush 102 descends, it acts as a pump or piston, forcing the fresh supply of adhesive upward between the brush and the wall of receptacle 154, to all parts of the brush.

The machine is particularly designed for use in applying cement to the inside of a bottomed shoe S which has just been turned and in which the lining L is pulled inside out, a molded counter C having been inserted by hand in the shoe. In the operation of the machine the applying brush 102 will be raised from the receptacle 154 in which it has become coated with cement, by the manipulation of the operator-controlled treadle rod 142. This, acting through the lever 120, will cause the brush to be raised to a position adjacent to the shield or support 150, in which position a portion of the periphery of the brush will be guarded by said shield. At the same time, the balance of the periphery and its lower end will be exposed to permit the free presentation of the lateral faces of the inside of the counter end of the shoe S to the applying brush as indicated in Fig. 2. As the operator faces the front of the machine (at the right in Fig. 1), he will hold the empty shoe upright with the heel end toward the machine and, guiding the shoe by the relation of the upper adjacent to the lacing slit to the support 150, will raise the shoe to insert the brush 102 in the shoe without danger of daubing the front part thereof. The shoe may then be manipulated to cause the brush to coat the desired portion of the inside of the shoe with the assurance that the forward part of the shoe will not become coated with cement. The shoe will then be removed and the lining replaced and smoothed down, either manually or by means of the mechanism described in the parent application, to which reference has been made above. With the mechanism shown, it will be necessary for the operator again to cause the depression of the treadle rod 142 so as to lower the applying brush 102 into the receptacle 154, to which a measured quantity of cement will have been delivered by the barometric supply tank 148. The pump action of the brush in entering the reservoir will cause this quantity of cement to flow over the whole outer periphery of the brush which, it will be remembered, is rotating constantly, and said brush will be ready for withdrawal to a position where it may be used for coating the inside of another shoe.

Having thus described my invention, what I claim as new and desire to secure by Letters Patent of the United States is:

1. A shoe machine comprising, in combination, a member formed and arranged to enter a shoe to coat the inside thereof with liquid, a receptacle for liquid in which said member is normally positioned, and means

to move said member out of the liquid in the receptacle to coat the inside of a shoe and thereafter to return it into the liquid.

2. A shoe machine comprising, in combination, a liquid-applying brush formed and arranged to enter a shoe to coat the inside thereof, a source of supply of adhesive, and means normally positioning said brush and said source relatively to one another to supply liquid to the brush and operable relatively to move said brush and said source to permit a shoe to be placed about the brush to have its inside surface coated thereby.

3. A shoe machine comprising, in combination, a liquid-applying brush formed and arranged to enter a shoe to coat the inside thereof, means to rotate said brush in engagement with the inside of a shoe, a receptacle for liquid in which the brush is normally immersed, and a member to lift the brush out of the liquid to permit engagement with the inside of a shoe.

4. A shoe machine comprising, in combination, a frame, a support thereon adapted to enter a shoe, a liquid coating applying member constructed and arranged for insertion into a shoe on said support to coat a portion of the inside surface of the shoe, and means for supplying liquid to said applying member.

5. A shoe machine comprising, in combination, a driven coating means adapted to be positioned inside a shoe off the last to coat with liquid one part of the inside of said shoe, and fixed means supported out of contact with said coating means to protect another part of the inside of the shoe from the action of the coating means.

6. A shoe machine comprising, in combination, means to coat with liquid one part of the inside of a shoe, and a shoehorn-like shield adapted to enter the shoe to protect from the action of the coating means another part of the shoe.

7. A shoe machine comprising, in combination, a source of supply of adhesive, a brush mounted for movement from a position to receive adhesive therefrom to a position within a shoe so as to apply the adhesive to the inside of the shoe, and a shield to protect part of the inside of the shoe from the action of the brush.

8. A shoe machine comprising, in combination, a rotary brush constructed and arranged to enter and to engage the inside of the counter of a shoe, and a member constructed and arranged to shield the forward part of the inside of the shoe from the action of the brush.

9. A coating machine comprising, in combination, an adhesive-applying member, means to rotate said member in contact with a piece of work, a receptacle for adhesive, and means to move said member axially into and out of the receptacle.

10. A coating machine comprising, in combination, a rotary brush, gearing to rotate the brush to apply a coating to a piece of work, a receptacle for liquid, said gearing being also constructed and arranged to rotate the brush while in the receptacle, and operator-controlled means for moving the brush axially into and out of the liquid in the receptacle while rotating.

11. A coating machine comprising, in combination, a shaft, a brush on the shaft, two-cycle treadle-controlled mechanism to raise the shaft during one cycle and lower it during the next, means to rotate the shaft in both raised and lowered position, and means to supply liquid to the brush in its lowered position.

12. A shoe machine comprising, in combination, an applying device constructed and arranged to enter and to apply a liquid to the inside of a bottomed shoe, and means to supply a predetermined quantity of fresh liquid repeatedly to said applying device for each shoe.

13. A shoe machine comprising, in combination, a brush constructed and arranged for insertion in a bottomed shoe thereby to apply liquid to the inside of the shoe, and means to deliver a measured supply of fresh liquid thereto for each shoe.

14. A coating machine comprising, in combination, a receptacle, means to supply a small quantity of liquid in the bottom of the receptacle, and an applying device of slightly smaller cross-section than the receptacle and movable thereinto to force the liquid upward between said device and the walls of the receptacle to supply it to the upper parts of the device.

15. A coating machine comprising, in combination, a receptacle open at the top and having a hole near the bottom, a reservoir to supply liquid thereto through the hole, said reservoir to contain liquid at a level higher than the hole and hermetically closed so that the atmospheric pressure will normally prevent the liquid from rising above the top of the hole in the receptacle, and a coating device slightly smaller in cross-section than the receptacle and movable thereinto to force the liquid by a pistonlike action upward between the device and the wall of the receptacle, to supply it to the upper parts of the coating device.

16. A coating machine comprising, in combination, a liquid-supplying reservoir in which the level of the liquid is normally maintained constant by atmospheric pressure, and a rotary brush axially movable into and out of the liquid in the reservoir.

17. A coating machine comprising, in combination, a fixedly mounted guide member to position a shoe, and means to coat the lateral faces of the inside of a shoe positioned thereby.

18. A shoe-cementing machine comprising a receptacle, means for supplying a measured quantity of cement to said receptacle, less than enough to fill the receptacle, and an applying device movable into said receptacle constructed and arranged nearly to fill the receptacle so as to displace the cement in the receptacle and cause it to flow over the whole peripheral surface of the applying device.
19. A shoe-cementing machine comprising an applying device mounted for movement to and fro from a supply position to an applying position, said device being rotatable about an upright shaft and mounted so that the applying device is exposed at the lower end of said shaft to allow the presentation of the inside of a shoe to said applying device.
20. A shoe-cementing machine comprising an upright shaft, an applying device rotatable about the axis of said shaft, and a shielding device surrounding a portion of the periphery of said applying device and leaving the bottom and rest of the periphery of the applying device exposed so that the inside of the counter portion of a shoe may be presented to the applying device without interference with the rest of the machine and the forward portion of the shoe may be protected from the undesired application of cement thereto.
21. A shoe-cementing machine having an upright shaft, an applying device rotatable about the axis of said shaft and mounted at the lower end of the shaft so that it is supported in exposed position to allow the presentation of the inside of a shoe thereto, and means for intermittently supplying cement to said applying device.
22. A shoe-cementing machine comprising a substantially cylindrical applying device rotatable about an upright axis, means reciprocating said applying device and rotating it about said axis at a plurality of elevations, and means for intermittently supplying cement to said applying device.

In testimony whereof I have signed my name to this specification.
